SPRING-HINGED TWO-PART RECEPTACLE

John J. Lynch, Metuchen, N. J.

Application July 26, 1945, Serial No. 607,203

6 Claims. (Cl. 220—35)

1

This invention relates to holders and in particular to a type designed to encase the brush end of a toothbrush so that the same can be kept in a sanitary condition and can be removed from and returned to the holder with a minimum of effort and time.

A particular object of my invention is to provide a holder in which all of the parts may be made from plastic or non-metal material and in which a novel molding of the parts will result in the reduction of the number of different parts that may be necessary to mold as separate units. A still further object of the invention is to provide a housing that is made in two identical parts, the same to be hingedly joined for relative opening and closing movement, the hinge portions of the housing parts to be so arranged that they interfit to provide for a solid hinging movement of the parts without sidewise twist or screwing action, whereby the parts will close evenly to provide a dust free construction. A still further object of the invention is to provide a structure wherein the connecting pin that hinges the parts together for opening and closing movement may be molded integrally with spring arms that serve as yieldable means for maintaining the parts of the holder closed and also prevent the relative movement of each part sidewise or laterally with respect to the other part, said spring means serving as a locking means to effectively hold the assembled structure together. A still further object of the invention is to provide a hinge pin having formed integrally therewith the spring arms referred to and in addition form the hinge pin of hollow molded form. While plastic construction is preferred, the use of non-rusting metal is within the scope of the invention, but the use of the hinge element of elastic plastic permits ready assembly of the parts and replacement at small cost.

A further object of the invention is the provision of means whereby the brush holders may be individually supported so that they can be placed in and removed from a rack without the necessity of removing any adjacent holder from the rack. Also, each individual holder may be employed alone and is so constructed that it can be laid on a flat surface, can be hung up on a nail or can be supported from a flat wall by the use of a vacuum cup. Each of the holders is so arranged in the rack that the whole group form a substantially unbroken front surface which can be used for combinations of letters making up a word, each individual holder also lending itself to the use on one side thereof of identifying

2

names or insignia and each holder being also formed so that one side or the other, whichever is outermost in the rack may show the simulation of a figure.

5 With these and other objects in view, the invention comprises certain constructions herein-after described and then particularly pointed out in the claims and a preferred embodiment of my invention is illustrated in the accompanying drawings, in which;

Figure 1 is a view in perspective of a holder and rack constructed in accordance with my invention.

10 Figure 2 is a view in perspective of a holder as it would appear out of the rack,

Figure 3 is a view in perspective of one of the like halves of a holder,

15 Figure 4 is a view similar to Figure 3 showing a half section turned at ninety degrees and illustrating how it can be combined with the half section of Figure 3 to form a whole holder,

20 Figure 5 is an enlarged fragmentary section taken on the line 5—5 of Figure 2 showing the relative position of a spring coil between the hub portions of the hinge,

25 Figure 6 is a view in side elevation partly in section, of a holder in individual use,

Figure 7 is a view in perspective of a holder shown supported against a wall by a vacuum cup,

30 Figure 8 is a plan view of the holder shown in Figure 7, the cup being shown in section,

Figure 9 is a view in side elevation showing a holder of slightly different conformation,

35 Figure 10 is a front view of the holder shown in Figure 9,

Figure 11 is a bottom view of the holder shown in Figure 9,

40 Figure 12 is a fragmentary view in section of the holder supporting portion of a rack showing the bevelled edges of the engaging surfaces of the holder and rack,

Figure 13 is a face view of a holder showing how the same can be embossed or engraved to simulate a figure,

45 Figure 14 is a view in end elevation of a form of rack and holder in which the depth of both is about alike,

Figure 15 is a face view of the rack and holders shown in Figure 14 showing how the latter may 50 present a substantially unbroken appearance across the front thereof to bear individual names or numbers or some form of advertising,

Figure 16 is a fragmentary plan view of the hinge hubs and means of holding the same together,

Figure 17 is a section on the line 17-17 of Figure 16 showing the integral construction of the spring and hinging means.

Figure 18 is a side view of the hinge and spring element.

Figures 19, 20, 21, and 22 show various forms of the hinge and spring elements.

Referring to the drawing in detail, 10 indicates a rack strip whose ends are offset as at 11 to be secured to a supporting surface, the intermediate section or reach of the rack 12 being shaped to present offset strips or fingers 13 in spaced relation with each other, the intermediate panels 14 constituting the body of the rack. The bottoms of the fingers 13 where they join the body of the rack afford a rest for the holders, which are held securely in place in the fingers and against the panels 14. The rack may be made of any material desired, plastic being preferable as it lends itself to easy cutting and shaping or molding.

The brush holder is made of identical parts that require one molding die and are shaped to provide a housing 15 of rectangular hollow form having side edge openings 16 and an opening for the shank of a brush in the bottom inclined wall 17, the opening indicated as at 18 being of any desired shape. The taper of the bottom wall 17, which may be flat or semi-circular in shape, drains off water that may be left in the brush when it is returned to the holder after use.

The housing 15 is formed with an integral edge flange at opposite edges thereof as at 20, which flanges slip in behind the fingers 13 to support the holder 18 in place in the rack. The distance between the fingers 13, which are in effect outstanding flanges, permits close fit therebetween of the housings 15 so that when one holder is put in place or removed it will not effect the position of the adjacent holder. Each holder may be removed individually. The fingers 13 have a spring action and grip the flanges 20 if desired, but this is unnecessary as the depth of the flanges 20 prevent any accidental lifting of the holder out of the rack.

The housing 15, two of which are combined to make a complete holder, is shaped to provide along its upper inner edge, a cylindrical hub portion 21 and an adjacent or contiguous hub seat portion 22, which latter is substantially of the same contour and radius as the exterior of the hub so that when the housings 15 are put together to form a holder, the respective hubs and hub seats fit together to provide a hinge structure that is long enough to prevent any relative skewing between the housings and to hold them closed evenly at the edges. The hub 21 and seat 22 are formed in the junction of the extension 23 with the housing body 15, it being understood that the entire housing unit is molded in one piece to provide the extension 23 to which may be attached by a rivet, a vacuum cup as at 24 or the extension may be provided with an opening 25 through which it may be hung on a nail. The outer surface of the extension 23 may be knurled so that the fingers will not slip when the finger extensions 23 are squeezed to open the housings 15 in their united holder construction. The inner wall 26 of said extension is slotted as at 27, the slot opening into the hub seat 22 at one side and bounding the end of the hub 21 at the opposite side. The slot is placed centrally of the housing 15 so that when two housings are united, the slot of each housing provides a con-

tinuous groove for the reception of a spring member 30 which as shown in Figure 5 may be a coiled spring whose convolutions 31 surround a hinge pin 32 passing through the hub portions 21 and spaced by the convolutions of the spring, whose ends 33 rest in the slots 27 and prevent lateral separation of the housings 15 by engagement with the side walls of said slots 21. In this form the coil of the spring member may frictionally engage the hinge pin which may be force fitted into the coiled part of the spring so that it will not have endwise movement, and so that heading of the pin will not be necessary.

In the preferred method, I would join the housings by the use of a single piece flexible plastic member of the forms shown in Figures 16 through 22 and consisting, in Figures 16, 17 and 18 of a pin member 34 whose elastic property is negligible having wings or blades 35 which are elastic enough to yieldably resist the movement of the finger pieces 23 toward each other in an opening movement of the holder to permit removal of a brush and provide the spring tension necessary to maintain the housings in relatively closed position. The spring blades 35 lie in the slots 27 and fit therein snugly enough to prevent relative sidewise movement of the housings. They prevent the pin portion from moving endwise and the holder is made from two different members, that is two like housing pieces 15 joined by one spring hinge member 34. The parts can be quickly assembled and are securely united when the member 34 is in place with its blades in the groove that is formed by the slots 27, the blades being part of a peripheral spacing flange 34A formed on the member 34, the blades being part of a peripheral spacing flange 34A formed on the member 34.

While I have shown this form of structure in connection with a tooth brush holder, it is evident that it can be employed in any structure in which like hinged parts are to be united for relative opening and closing movement as in a box construction for use in any manner.

While reference is made to flexible plastic, it is evident that the form of hinge member may be embodied in a metal structure and in Figure 20, a form of either plastic or metal structure is shown consisting of a pin forming tube 40 which fits into the hubs 21 of the united housings 15 so that the integrally formed wings or blades 41 thereof will rest in the slots 27 to lock the housings together as shown in Figure 2 and provide the spring action to yieldably keep the parts closed. The form of the blade portions 35 in Figure 17 may be varied as shown in Figure 19 in which they extend as at 42 tangentially to the pin forming portion 43 of the hinge element. In Figure 21, the use of a spring strip 44 is illustrated as providing blade portions 45 and a central loop 46 which may grip the separate pin 46A used as a hinging element to cooperate with the member 44 in holding the housings 15 in united relation.

The bore 28 of the hubs 21 is molded or drilled in the hubs and the hinge pin member is slipped into one of the hubs of a housing and then the other like housing is slipped over the exposed end of the hinge pin member and the blades snap into the slots 27 and the device is completely assembled, the parts are locked together and the housings may be squeezed open against the spring action of the blades and will snap closed when the finger extensions are released, to imprison the bristle end of the brush within the holder.

As shown in Figure 22, the hinge pin 48 may be grooved as at 49 intermediate its ends to permit the retention of a spring blade 50, either or both of which may be made from metal or plastic.

In the Figures 14 and 15, the holder is shown as being about as deep as the rack and the edge flanges 52 engage within the turned over strips 53 so that the holders are supported in the rack and present along their front faces a substantially unbroken wall. Each holder may be identified as by the name of the individual whose toothbrush is housed or by a number as desired and the whole may form a complete advertisement. Further, the upper ends of the finger extensions 23 when the holders are in place in the rack provide a cradle into which may be laid the tube of toothpaste so that it is convenient for use. For the use of children, the holders may be ornamented or molded in simulation of human or animate fingers as shown in Figure 13 as at 55, in this instance the holder being of slightly different shape in that the finger extensions are shortened as at 56 and the wall of the housing is curved as at 57. When the holder is used individually, it may be supported on a pin or nail passing through an opening 25 formed in the end of the finger extension 23 or may be provided with a vacuum cup at the end of one of said extensions as at 24, Figures 7 and 8. The upper ends of the rack panels and fingers, 14 and 13 respectively, and the lower edges of the flanges 20 may be bevelled or edged as at 60 to facilitate the insertion of the holders into the rack, as shown in Figure 12.

My invention is not to be restricted to the precise details of construction shown since various changes and modifications may be made therein without departing from the scope of the invention or sacrificing the advantages derived from its use.

What I claim is:

1. A receptacle comprising like housing members, each member being shaped to provide a hub and a hub contacting seat in axial alignment, a slot in each member intermediate hub and seat, and extending laterally therefrom, a pintle passing through the hubs when the members are reversely united and flexible means extending laterally from said pintle to engage the slot in each member and secure said members in receptacle forming relation and yieldably resist relative opening movement thereof.

2. A receptacle comprising housing members made from the same plastic molding die, each member being shaped to provide a hub and a hub seat in axial alignment each hub and seat being in contact when the members are united, a slot intermediate said hub and seat and extending the body of each member, a pintle passing through the aligned hubs and slot engaging spring arms extending from said pintle to secure said members in receptacle forming relation and to yieldably resist relative opening movement of the members.

3. A receptacle comprising like housing members, each member being shaped to provide an extending finger piece, a hub and a hub seat in adjacent axial alignment, a slot intermediate said hub and seat extending into the finger piece, and a pivot member having integral oppositely projecting flexible blades for engaging the slot portions of the members to secure the same laterally in matching receptacle forming associa-

tion and yieldably oppose the hinging movements of the members relatively to each other in one direction.

4. A holder comprising plastic units cast in the same die, each unit being shaped to provide a receptacle portion, axially aligned single hub and hub contacting seat portions each extending substantially half the width of the unit, said receptacle portion having a groove extending laterally from said hub seat at the inner end of said hub, a hinge pin passing through the hubs of two assembled units and laterally extending members associated with said hinge pin for engagement with the grooves of said units for holding the latter widthwise in receptacle forming relation and yieldably resisting relative hinging movement therebetween.

5. A holder comprising relatively hinged members each including, when the members are reversely united, a cooperating hub and seat portion and formed to provide grooves extending laterally from a point between said hub and seat portions, a hinge pin passing through said hub portions and having integral flexible extensions for engagement with said grooves to yieldably resist hinging movement of the members in one direction, and said extensions and grooves constituting means for securing the pin in position in the hubs and preventing relative lateral movement between said members.

6. A container made from two identical half members each shaped to provide hub and hub seat portions for interfitting axially aligned contactual relation when the members are reversely united to form the container, a slot in each half member extending laterally from the contiguous ends of the hub and seat portions, a pintle passing through said hub portions and means associated with the pintle for engaging each slot to secure the halves in container forming relation and to yieldably resist pivotal movement therebetween.
